UNITED STATES PATENT OFFICE

WILLIAM PLATTS KELLETT, OF NEW YORK, N. Y.

FLOOR CONSTRUCTION

Application filed January 21, 1929. Serial No. 333,933.

The principal objects of the invention are to provide a floor surface particularly adaptable for warehouses, loading platforms, freight car floors and other places where the floors are subject to heavy trucking traffic.

A further object is to devise a method of construction which will enable the presentation of an even floor surface which may be laid very quickly and accurately at moderate cost.

The principal features of the invention consist first, in the novel construction and arrangement of flanged metal members nested together to form a floor surface, and second, in the novel method of laying such metal members on a plastic base.

In the accompanying drawings, Figure 1 is a perspective view of a section of floor showing the manner of laying the metal surface in multiple units.

Figure 2 is a perspective view showing the underside of one of the multiple unit surfacing members.

Figure 3 is an enlarged perspective detail showing the construction of the sheet metal surfacing units.

Figure 4 is an enlarged cross-sectional detail of a section of the floor.

Figure 5 is a plan view of one of the blanks.

Figure 6 is a section of a car floor.

In warehouses, factories, freight handling platforms and railway freight cars where wheel trucks are continually used carrying heavy loads, cement floors are pulverized on the surface and wood floors are scored and chipped and it is desirable to provide a surface which will obviate these difficulties other than by the use of boiler plate which is costly and difficult to retain in place.

In carrying this invention into effect flanged sheet metal blocks A are produced which are adapted to be fitted together and bedded into a plastic base.

These sheet metal blocks may be of any desirable shape but as are herein shown, they are of an oblong form and are pressed up from blanks 1 as shown particularly in Figure 5, the flanges 2 and 3 being notched at the corners and having elongated slots 4 in the centre of the length of the side flanges

3 and short slots 5 adjacent to each of the ends, also holes 6 are arranged preferably one-quarter of the length of the block from each end and holes 7 are punched in the top of the sheet.

The blank thus formed is pressed up, being flanged along the dotted line 8 so that the corners will be drawn below the flat top surface.

The under structure of the flooring may be concrete but it is preferable to lay a surface of asphalt on a concrete base.

The flanged metal members are bedded into the concrete or asphalt base while it is in its plastic form and fit snugly together.

The air holes 7 formed in the top faces of the block allow the escape of air from underneath the flanged members as the flanges are forced downwardly into the plastic material and the plastic material flows through the slots 4 and 5 interlocking the members together.

While these members may be placed in position individually in a manner similar to the laying of tile, it is preferable that they be laid in multiple units and for that purpose the side flanges are provided with the holes 6 arranged so that when the blocks are staggered the holes of the opposite ends of the blocks are in register and fastening pins or wires 9 are passed through the flanges of a suitable number of the blocks to form a unit which can be easily handled. Such unit may be ten or twelve feet long and from two to four feet or more in width. It is flexible and can be readily placed in position and matched to blocks already laid and when placed on top of the plastic foundation it is pressed slowly into place so that the plastic fills in to the space between the flanges, thus supporting the sheet metal so that it will not dent.

In assembling a plurality of blocks into a multiple unit, it may be found desirable to place washers 10 between the adjacent side flanges through which the fastening pins 9 are threaded, thus spacing the longitudinal side flanges of the various members apart. This will allow the plastic material to flow upwardly partly between the flanges but par-

ticularly will provide spaces to permit the reception of a plastic applied from the top, such as hot asphalt or tar, poured over the surface to fill in the cracks.

3. This will eliminate the gathering of dust and dirt and will also act to completely deaden any resonance that might possibly exist in the metallic structure.

Flanged sheet metal blocks as tile for covering walls but it is believed to be entirely new to utilize such metal structures as a floor covering and particularly to embed such devices in a more or less resilient plastic. This arrangement produces a very novel and useful result.

10 In the application of the invention to railway cars as shown in Fig. 6, corrugated metal plates 11 are placed across the car beams and a cement base 12 of a suitable plastic composition is laid thereon and the flanged metal blocks A are bedded in the plastic base.

15 What I claim as my invention is:

1. A method of constructing a floor or other surface, consisting in preparing a suitable base, pivotally connecting a flanged block at spaced points in its length with a plurality of other flanged blocks to form flexible groups, then placing said groups on said base in overlapped relation.

20 2. A method of constructing a floor or other surface consisting in providing a plastic base, pivotally connecting a plurality of flanged blocks together in break-joint overlapped relation by threading a length of wire rod through aligned openings in the flanges of the blocks, bending the end of the length of wire laterally to prevent withdrawal thereof, placing the connected group of blocks on the plastic base, and applying pressure thereto to embed the flanges of the blocks in the base.

25 3. In a floor surface, blocks having down-turned side flanges, each of said blocks having pintle openings in the side flanges spaced equidistant from the ends of the block, the interlock openings in the side flanges of said blocks adapted to register to form interconnections between the interiors of the respective blocks, pintle openings of one of said blocks being adapted to register with the pintle openings of a plurality of other blocks, and pins extending through the registering pintle openings and pivotally connecting the blocks in a flexible group with said interlock openings in permanent register.

4. In a floor surface, blocks having down-turned side flanges, each of said blocks having pintle openings in the side flanges adapted to register when said blocks are placed in overlapping relation, and a length of wire threaded through the openings in said side flanges and pivotally connecting a plurality of said blocks together, the ends of said wires being displaced laterally to lock the blocks against separation.

5. A multiple paving unit comprising a group of blocks flanged downwardly at the sides and having openings in the flanges, said blocks being pivotally connected together by their flanges in staggered break-joint relation with flange openings in register.

6. In a floor surface, the combination with a plastic base, of a plurality of flanged sheet metal blocks having their flanges pivotally connected together at spaced points in the length thereof, the flanges being embedded in the base.

7. A wear-resisting surface comprising a plurality of flanged blocks formed of sheet metal adapted to be placed side by side and embedded in a plastic base, the adjacent side flanges of said blocks having triple spaced openings adapted to register to form intercommunication between the interiors of the respective blocks forming an interlock with the plastic material, and means for flexibly connecting said blocks in groups with flange openings of the adjacent blocks in permanent register.

8. In a floor surface, blocks having down-turned side flanges, each of said blocks having pintle openings in the side flanges adapted to register when said blocks are placed in overlapping relation, a length of wire threaded through the openings in said side flanges and pivotally connecting a plurality of said blocks together, the ends of said wire being displaced laterally to lock the blocks against separation, and spacing means interposed between said blocks.

9. In a floor surface, blocks having down-turned side flanges, each of said blocks having pintle openings in the side flanges adapted to register when said blocks are placed in overlapping relation, a length of wire threaded through the openings in said side flanges and pivotally connecting a plurality of said blocks together, the ends of said wire being displaced laterally to lock the blocks against separation, and spacing washers threaded on said lengths of wire between the adjacent side flanges of the blocks and spacing the latter apart.
